UNITED STATES PATENT OFFICE.

JOHN A. THOMAS, OF COLUMBUS, OHIO.

APPARATUS FOR PREVENTING SPONTANEOUS COMBUSTION IN COAL PILES.

1,399,036.

Specification of Letters Patent.

Patented Dec. 6, 1921.

Application filed October 12, 1918. Serial No. 257,913.

To all whom it may concern:

Be it known that I, JOHN A. THOMAS, a citizen of the United States, residing at Columbus, in the county of Franklin and 5 State of Ohio, have invented certain new and useful Improvements in Apparatus for Preventing Spontaneous Combustion in Coal Piles, of which the following is a specification.

10 This invention relates to an apparatus for and process of preventing spontaneous combustion in storage coal piles.

It is well known that great losses have been sustained through the burning of coal 15 when stored in piles and that the fire which is generated within the coal pile is recognized as the result of what is called spontaneous combustion; therefore the object of my invention is to introduce and pass 20 through the coal air in sufficient volume and under sufficient pressure to maintain the coal in a sufficient dry state to prevent combustion taking place.

The preferred apparatus for accomplishing this object is illustrated in the accompanying drawing in which,

Figure 1 is a plan view of a coal receptacle having my improved air supplying means connected therewith,

30 Fig. 2 is an enlarged transverse section of one of the air conducting pipes,

Fig. 3 is a view in elevation of the end portion of one of said pipes on a scale slightly reduced from that shown in Fig. 2,

35 Fig. 4 is an enlarged sectional view on line 4—4 of Fig. 1, and

Fig. 5 is a transverse section of the coal receptacle.

Similar characters of reference denote 40 like and corresponding parts throughout the several views of the drawing.

For the purpose of illustrating my apparatus I have shown the erect angular coal receptacle 1 the walls of which may be formed 45 of cement or other suitable substance. It will be understood however that such receptacle may in itself be omitted and the coal piled on the ground in the space which is occupied by the receptacle or piled on a 50 suitable concrete flooring or base for instance as that indicated at 3. 4 represents parallel pipes of which there may be any desired number, one set or battery of these pipes extending through each end of the 55 receptacle and to a point near the center of the length of the receptacle. The pipes have

their inner ends closed and are all in floor recesses 5 so that their upper surfaces do not project undesirably beyond the floor surface of the piling space or receptacle. 60 The pipes 4 are suitably perforated in their upper halves as shown at 4^a in Figs. 2 and 3 for the reasons hereinafter given. The pipes 4 of each set or battery have their outer ends connected with a manifold or secondary supply tank 6 the latter having at one end a valve controlled water outlet 7.

At a suitable point preferably adjacent to the piling space or coal receptacle is provided a main air supply tank 8 to which air 70 is pumped under pressure from a suitable form of air pump 9. From the ends of the supply tank 8 lead air pipes 10 the latter connecting respectively with the secondary supply tanks 6. At suitable points in the 75 air pipes 10 I provide cut off valves 11.

By reference to Fig. 5 of the drawing it will be seen that the floor of the receptacle 1 is preferably inclined toward one side of the receptacle or piling space and by reference to Fig. 4 it will be seen that the perforated pipes 4 are inclined outwardly in the direction of the length of the receptacle. When a walled receptacle such as that shown at 1 is employed I provide at a point opposite the floor surface and within the wall of such receptacle a conduit 12 into which lead ports 13 formed in the receptacle at the junction of one of said walls and the floor of the receptacle. It will be understood that 80 owing to the incline of the floor 3 toward the outlet ports 13 water which might otherwise accumulate in the bottom of the receptacle may find an outlet through the conduit 12. It will be likewise clear that the incline of 85 the pipes 14 in the direction of the length of the receptacle and toward the ends thereof will insure the carrying into the secondary supply tank any water which may otherwise accumulate in said pipes.

100 In operation it will be understood that the air which is pumped into the main supply tank 8 will be distributed through the pipes 10 when the valves 11 are open thence into the tanks 6 and pipes 4 from which pipes 105 the air may pass outward through the perforations 4^a and into and through the body of coal which is designed to be supported on the floor 3 and above the pipes 4.

110 It is a recognized fact that spontaneous combustion in coal piles is largely the result of the action of water on the interior of

the pile. Water passing into the coal pile as a result of rains and melted snow results when in contact with the coal in causing decomposition of the coal to a greater 5 or less extent and combines with the carbon content to produce certain carbon gases. This chemical reaction is of necessity accompanied by heat and after a predetermined temperature point is reached the carbon content of the coal as it is released combines with the oxygen of the air with the result that fire is generated. By the means which I have described of passing air under pressure through the perforations of 10 the pipes and into the body of coal it will readily be understood that the coal will be kept sufficiently dry to prevent the process of oxidation above described. In case there should be an accumulation of water on the 15 floor or in the lower portion of the coal pile such water may find its way outward down the lateral incline of the floor of the receptacle through the ports 13 and into the conduit 12 from which the water may be discharged at any convenient point.

It will also be observed that by the provision of the valves 7 in the tanks 6 water which may possibly find its way through the perforations of the pipes 4 and into said 20 pipes will be discharged into the tanks 6 from which it may be permitted to pass outward by opening the valves 7.

It will be noted that in the drawing I have shown two sets or batteries of the pipes 4 and that I have provided the air conducting pipes 10 with the valves 11 thus permitting 25 of one set of the pipes 4 being closed to the incoming air in case there is coal piled in one part of the receptacle only.

By the use of the process and apparatus described it is obvious that spontaneous combustion in coal piles may be prevented thereby effecting a great saving of fuel and expense.

What I claim is:

1. An apparatus for storing coal comprising a base having a plurality of grooves formed in its upper surface, pipes disposed to occupy said grooves, said pipes having a 50 plurality of apertures formed therein, and means for supplying air under pressure to said pipes.

2. An apparatus for storing coal comprising a receptacle including a base and perpendicular side walls, said base having a 55 plurality of grooves formed in its upper surface, pipe members disposed within said grooves and formed with outwardly opening apertures, and means for supplying air under pressure to said pipes.

3. An apparatus for storing coal, comprising a receptacle including a base and substantially perpendicular side walls, the upper surface of said base being provided with grooves, pipe members disposed to occupy 60 said grooves, said pipe members being formed with rows of outwardly opening apertures, means for supplying air under pressure to said pipe members, and the upper surface of said base being longitudinally and transversely inclined to provide a discharging medium for accumulated water within said receptacle.

4. The structure as specified in claim 3, in combination with a discharging duct for 75 water located contiguous to the lower transverse side of said base.

5. An apparatus for storing minerals comprising a base, conduits provided in the base below the upper surface thereof, said conduits being provided with longitudinally disposed outlet openings, and means for forcing a gas through said conduits, whereby said gas will be discharged from said 80 openings and permitted to pass through a 85 body of relatively loose mineral matter positioned upon said base and over said conduits.

6. An apparatus for storing minerals, comprising a base having a channel formed 90 therein, a conduit positioned within said channel and arranged to extend longitudinally thereof, said conduit being provided with longitudinally disposed outlet openings, and a power driven fluid circulating 95 device in communication with said conduit and operative to force a fluid therethrough, whereby said fluid will be permitted to issue from said openings and to pass through a body of relatively loose minerals deposited 100 upon said base and over said conduit.

In testimony whereof I affix my signature.

JOHN A. THOMAS.
